UNITED STATES PATENT OFFICE.

ALFRED W. BRUCE, OF NEW YORK, N. Y.

SUPERHEATED-STEAM THROTTLE VALVE.

Application filed April 25, 1923. Serial No. 834,480.

To all whom it may concern:

Be it known that I, ALFRED W. BRUCE, of New York, in the county and State of New York, have invented a certain new and useful Improvement in Superheated-Steam Throttle Valves, of which improvement the following is a specification.

My invention, while relating more particularly to throttle valves for superheated steam locomotive boilers, is not limited to such specific application, and its object is to provide a throttle valve which shall be desirably applicable in connection with standard appliances for superheating steam, and which shall have its receiving and delivering pipes entirely enclosed in the shell of the boiler in which it is installed.

The improvement claimed is hereinafter fully set forth:

In the accompanying drawings: Figure 1 is a view, partly in side elevation and partly in section, on the line 1—1 of Fig. 4, of a locomotive boiler, illustrating an application of my invention; Fig. 2, a horizontal section of an enlarged scale, of the connection between the stand pipe and dry pipe; Fig. 3, a plan or top view of the smoke box and forward portion of the waist of the boiler; Fig. 4, a vertical transverse section through the smoke box, on the line 2—2 of Fig. 3; Fig. 5, a similar section, on an enlarged scale, on the line 3—3 of Fig. 1; Fig. 6, a similar section, on the line 4—4 of Fig. 1; Fig. 7, a plan view of the main throttle valve; and, Fig. 8, a partial bottom view, on an enlarged scale of the main throttle valve, with the valve stem in section.

In the practice of my invention, referring descriptively to the specific embodiment thereof which is herein exemplified, I provide a throttle box or chest, 1, in which the main throttle valve, 3, is fitted, said throttle box being supported in a sheet metal casing, 2, of rectangular horizontal section, and having a flat or substantially flattened top, which casing is secured to the smoke box, 9, of a steam boiler of the locomotive type, and closes a correspondingly shaped opening in the top thereof. It will be noted that the casing 2 forms part of the shell of the smoke box 9, and is substituted for the ordinary circular arc upper portion thereof, in order to present rectangular side spaces which permit the elevation of the throttle box and its connections, above the highest

horizontal level which would otherwise be available, with a corresponding reduction of the degree of obstruction of the smoke box. The stack, 11, of the boiler, passes through the casing, 2, which is connected to a flange, 11^a, on the stack, and the throttle box, 1, is located in the casing, between the front thereof and the stack, as shown in Figs. 1 and 3, and is connected to the top plate of the casing by bolts, 2^a, passing through a flange, 14, at its top, abutting against said top plate.

Saturated steam is supplied from the steam space of the boiler to an open topped stand pipe, 12, extending upwardly in a dome, 13, on the waist, 10, of the boiler, and connected, at its bottom, in the usual manner, as by hook bolts, 14, to the rear end of a steam supply pipe or dry pipe, 15. The stand pipe is supported on hangers, 12^a, bolted to the shell of the boiler. The forward end of the dry pipe is connected to the saturated steam compartment of a superheater header, 16, of any suitable known construction, which is, as usual, located in the smoke box, 9, and is provided, with a plurality of superheater units, 16^a, located in boiler tubes, 10^a, of enlarged diameter. The superheated steam compartment of the header, 16, is connected, by two pipes, 16^b, leading forwardly on opposite sides of the stack with nozzles, 1^b, on the throttle box, 1. By reason of the stack being located between the superheater header and the throttle box, the application of two laterally disposed connecting pipes, 16^a, as shown, is, for structural reasons, preferable to that of a single pipe.

The relative disposition of the throttle box, stack, superheater header and side steam pipes, is of importance, from a practical standpoint, in several particulars. It admits of the application of smoke box throttles, without limitation by the existing distance between the front tube sheet and the stack, which distance, especially in the case of locomotives with two wheel leading trucks, is often so limited as to prevent such application. It further provides a symmetrical connection between the superheater header and the throttle box and, as a special feature of advantage is adapted to application on existing locomotives, equipped with a conventional type of superheater header having steam outlets on opposite sides, which ad-

vantage is not presented where only a single outlet connection is adopted, as in all prior constructions, within my knowledge or information.

5 In order to enable the supply of steam to the dry pipe, superheater header, and throttle box, to be cut off, in exceptional cases, when desired, as for regrinding or other repairs, a supplemental throttle valve, 17, is 10 fitted in the stand pipe, 12, and controls communication between the steam space of the boiler and the stand pipe and its connections. The supplemental throttle valve is manually operable by a hand wheel, 17^a, secured on a stem, 17^b, passing through a stuffing box, 17^c, in the dome, and coupled to the threaded stem, 17^d, of the valve, which stem engages an internal thread on a plate, 17^e, secured, detachably, to the stand pipe. 15 20 The throttle box, 1, is open, at bottom, to two laterally extending nozzles, 1^c, which are connected to the steam supply pipes, 18, leading to the cylinders of the locomotive, and communication between the superheated steam compartment of the header, 16, and the steam supply pipes, 18, is normally and directly controlled by a main throttle valve, 3, which may be of any suitable and preferred construction that is operable from the outside of the boiler. The main throttle valve which is herein exemplified, accords, in all essential particulars, with that set forth in an application for Letters Patent of the United States, filed 30 by me March 28, 1923, Serial No. 628,258. It is not, therefore, claimed as of my present invention, and will be only generally herein described.

As shown in Figs. 6, 7 and 8, the main 40 throttle valve, 3, is of the single seated lift or poppet type, and is connected, with the capacity of a limited degree of relative movement, to a stem, 5, by the longitudinal movement of which it is brought against, or 45 moved away from, an inclined seat, 1^a, in the throttle box, to prevent the admission of, or admit, as the case may be, superheated steam from the header to the steam supply pipes, 18. A balancing sleeve, 3^a, 50 which is open, at its end further from the valve, is formed integral therewith, and extends therefrom into a superimposed balancing chamber, 4, in the upper portion of the throttle box. The balancing chamber 55 is closed by a removable cap plate, 4^a, having a properly packed stuffing box, 4^b, through which the valve stem passes. A small port, 3^c, formed in the wall of the balancing sleeve, provides for the leakage 60 of steam into the balancing chamber. A central passage, 3^b, surrounding the valve stem, and of greater diameter than said stem, is normally closed by a pilot valve, 8, fixed on the valve stem. Said stem carries, adjacent to its lower end, a washer, 65

5^a, the position of which is adjustable by a nut, 5^b, engaging a screw thread on the stem. The metal of the valve which surrounds the bottom of the central passage, 3^b, is radially recessed or channeled by grooves, 70 3^d, to permit the free flow of steam from the passage, 3^b, when the washer, 5^a, bears against the bottom of the throttle valve.

In operation, the throttle valve, being normally seated, it is subjected to downward pressure and held to its seat by the boiler steam in the balancing chamber. When it is desired to admit steam to the supply pipes, the preliminary upward movement of the valve stem by the actuating mechanism, unseats the pilot valve, and brings the washer, 5^a, to a bearing against the bottom of the throttle valve. The steam in the balancing chamber is then exhausted therefrom into the supply pipes, and the 80 85 throttle valve is relieved from the downward pressure which held it to its seat. By the continued upward movement of the valve stem, the throttle valve may be unseated to any desired degree. There being a continuous relief of pressure in the balancing chamber, during the period that the throttle valve is unseated, no resistance is opposed to its upward movement.

The throttle valve is seated by the downward movement of the stem, 5, in bringing the pilot valve, 8, to its seat, and, after being seated, is held to its seat by the leakage of steam into the balancing chamber. 100

The stem, 5, passes through a stuffing box, 4^b, in the cover, 4^a, of the balancing chamber, and a jaw, 6, is fixed upon its outer end, for connection to any suitable actuating mechanism, which does not form part of my present invention. In the instance exemplified, a manually operable lever, 19, is connected to the valve stem, through the intermediation of a pull rod, 21, compensating lever, 22, and rod, 22^a, as in the patent of J. J. Jones, No. 1,229,968, 105 110 dated June 12, 1917.

My invention attains, in practice, by the application of improved structural features, the well recognized advantage of the interposition of a throttle valve between a source of superheated steam supply and the engine or engines in which the superheated steam is to be utilized, which interposition is not broadly new and, therefore, is not claimed as of my invention. It is also substantially advantageous in the particular that the throttle box and its connections are completely enclosed within the shell of the smoke box, with a minimum of expansion of the volume thereof, and that their location therein is such as avoids impairment of the draught, or interference with the application of standard spark arresting appliances, and presents capability 120 125 130 of application in existing locomotives

which is not existent in prior constructions, so far as my knowledge and information extend.

I claim as my invention and desire to secure by Letters Patent:

1. In a boiler of the locomotive type, the combination of a casing, having a flattened top and closing an opening in the top of the smoke box of the boiler; a superheater header in the smoke box; and a throttle valve, located in and supported on the casing, between the stack and the front thereof, and controlling communication between the superheater and the steam supply pipes 10 in the smoke box.
2. In a boiler of the locomotive type, the combination of a casing, having a flattened top and closing an opening in the top of the smoke box of the boiler; a superheater header in the smoke box; a throttle box, located in and supported on the casing, between the stack and the front thereof; upper lateral connections, leading from the superheater header to the throttle box; steam supply pipes in the smoke box; a bottom connection leading from the throttle box to said pipes; and a throttle valve, fitted in the throttle box and controlling communication between the upper and bottom connections 20 thereof.
3. In a boiler of the locomotive type, the combination of a superheater header, located in the smoke box of the boiler; a saturated steam dry pipe, leading into said header; a casing, closing an opening in the top of the smoke box, and surrounding the

stack of the boiler; a throttle box, located in and supported on said casing, between the stack and the front thereof; superheated steam connections leading from the superheater header into said throttle box; steam supply pipes, leading out of said throttle box; and a throttle valve, fitted in said throttle box, and controlling communication between the superheated steam connection 40 and the steam supply pipes.

4. In a boiler of the locomotive type, the combination of a casing, secured to and closing the top of an opening in the smoke box of the boiler; a throttle box located in said casing and having a top flange secured thereto; lateral connections leading to a superheater header; and lower side nozzles, leading to steam supply pipes; and a throttle valve, fitted in said throttle box and controlling communication between the superheater header and steam supply pipe connections. 50

5. In a boiler of the locomotive type, the combination with the smoke box thereof, of a stack; a superheater header in the smoke box located in rear of the stack and having side steam outlets; a throttle box in the smoke box interposed between the front thereof and the stack; side steam supply pipes leading therefrom; side pipes connecting the steam outlets of the superheater header with the throttle box; and a throttle valve fitted in the throttle box and controlling communication between said box 60 and the side steam supply pipes.

ALFRED W. BRUCE.
